BED DAVENPORT

Irvin C. Poskin, Los Angeles, Calif.

Application October 27, 1944, Serial No. 560,607

8 Claims. (Cl. 5—38)

1

This invention relates to a bed davenport.

Speaking more specifically, the invention relates to a sofa which is provided with a swingable back carrying means whereby it is supportable upon the floor when adjusted in a horizontally extending position to convert the sofa into a bed.

One object of the invention is to provide a sofa with a swingable, horizontally supportable back which extends the entire length of the bed or seat portion of the sofa, so that the lowering of the back to a horizontal position will increase the width of the entire bed or seat portion.

Another object of the invention is to provide, for a swingable sofa back which carries legs to support it in a horizontal position, a combined means to hold said legs in recesses provided for them in the sofa's back, and at the same time to latch said back in its upstanding position.

Yet another object is to provide a more simple, sturdy means for swingably connecting a back member to the sofa in such a manner that said member, when in the extended position, will be better supported along its inner edge portion.

Other objects, advantages and features of invention will hereinafter appear.

Referring to the accompanying drawing which illustrates what at present is deemed to be a preferred embodiment of the invention,

Fig. 1 is a perspective view looking at the rear side of the device when adjusted for use as a sofa, the down position of the back being indicated by dotted lines.

Fig. 2 is an end view of the structure shown in Fig. 1.

Fig. 3 is a fragmentary rear elevation of one end portion of the device, a part of the covering being removed so as more clearly to disclose underlying parts.

Referring in detail to the drawing, the sofa shown comprises a seat portion 5, a pair of approximately rectangular upstanding end pieces 6 and a back member 7, the latter having the lower corner portion of each of its ends pivoted to the adjacent end member 6 by a pivot bolt 8.

The back member 7 comprises a rectangularly shaped frame having an upper side piece 9, a lower side piece 10 and at each end an outer crosspiece 11 and an inner crosspiece 12, the latter crosspiece being in a parallel, inwardly spaced relation to the former, thus affording a clearance 13 between said crosspieces in the upper part of which is an extensible leg 14 carried by a pivot pin 15.

A stationary latching element, preferably a staple 17 is secured to the upper back portion of

2

each end piece 6 to cooperate with a hook 18 pivoted at 19 to that part of the end piece 11 which is adjacent to said staple when the back 7 is in the upwardly directed position shown in the drawing. Said hook 18, at the side of its pivot which is opposite to its staple-engaging portion, is furnished with a tail-piece 20 which, when the hook is engaging the staple to keep the back in its upwardly directed position, prevents the adjacent leg 14 from swinging out of the space 13 designed to house it when the device is adjusted for use as a sofa. As best shown in Fig. 2, said tail-piece 20 is slightly arcuate so as to give it a backward deflection that will cause it more smoothly to pass over the housed leg 14.

Describing additional structural details, each end piece 6, as illustrated in Fig. 3, comprises spaced apart vertical side walls 6a and 6b, a top wall 6c and a bottom wall 6d. The pivot pin 8 consists of a bolt which extends through the crosspieces 12 and 11 of the back member 7, said pin having a projecting end portion for which the wall member 6b affords a bearing. A washer 21 is shown surrounding the pin 8 and serving as a spacer between the end of the back member and the adjacent end piece 6. A nut 8n screwed onto the bolt 8 completes this part of the structure.

The sofa is designed to be upholstered in the usual manner and may have the outer surfaces of its end pieces 6 and back 7 covered with ornamental sheet material 22.

Preparatory to swinging the back 7 down to convert the sofa into a bed the hooks 18 will be withdrawn from the staples 17, thus causing their tail-pieces 20 to disengage the free end portions of the legs 14, so that gravity may swing said legs out of their recesses 13 into position for supporting the downswung back 7 in a horizontal position.

What is claimed is:

1. A sofa having an elongated seat portion supported by and between end pieces which project above the ends of said seat portion, a back member extending substantially the entire length of said seat portion and hinged adjacent to the back side thereof to swing from an upstanding to a substantially horizontal position and vice versa, legs having end portions pivotally attached to said back member, and latching means to at times hold said back member in an upstanding position, said latching means comprising stationary parts carried by said end pieces and movable parts carried by said back member, said movable parts, when in the latched position, overlying the

free end portions of said legs to maintain them in an inswung relation to said back member.

2. A sofa having an elongated seat portion supported by and between end pieces which project above the ends of said seat portion, a back member extending substantially the entire length of said seat portion and hinged adjacent to the back side thereof to swing from an upstanding to a substantially horizontal position and vice versa, legs having end portions pivotally attached to said back member, and latching means to at times hold said back member in an upstanding position, said latching means comprising stationary parts carried by said end pieces and hooked members pivoted to said back member, said hooked members each having a hook at one side of its pivotal mounting and a tailpiece at the opposite side thereof, said tailpieces being positionable to overlie the free end portions of said legs to keep them in an inswung relation to said back member when the hooks are in engagement with the aforesaid stationary parts of the latching means.

3. A sofa having an elongated seat portion supported by and between end pieces, a swingable back member comprising an elongated frame having at least two adjacent spaced apart cross-pieces at each of its ends, a pivot pin projecting from each end of said frame and having a connection to the end pieces, each pivot pin being located adjacent to that side of said frame which is lowest and extending through both the cross-pieces at each end of the frame respectively and projecting therebeyond into the adjacent end piece which affords a bearing for the projecting portion of said pivot pin, legs carried by the free side portion of said swingable back member, and latching means carried by the sofa to maintain said back member in an upstanding position when the device is used as a sofa.

4. A sofa having an elongated seat portion supported by and between end pieces, a swingable back member comprising an elongated frame having at least two adjacent spaced apart cross-pieces at each of its ends, and a pivot pin projecting from each end of said frame and having a connection to the end pieces, each pivot pin being located adjacent to that side of said frame which is lowest and extending through both the crosspieces at each end of the frame respectively and projecting therebeyond into the adjacent end piece which affords a bearing for the projecting portion of said pivot pin.

5. A sofa having an elongated seat portion supported by and between end pieces, a swingable back member comprising an elongated frame having at least two adjacent spaced apart cross-pieces at each of its ends, a pivot pin projecting from each end of said frame and having a connection to the end pieces, each pivot pin being located adjacent to that side of said frame which is lowest and extending through both the cross-

pieces at each end of the frame respectively and projecting therebeyond into the adjacent end piece which affords a bearing for the projecting portion of said pivot pin, and latching means carried by the sofa to maintain said back member in an upstanding position when the device is used as a sofa.

6. A sofa having an elongated seat portion supported by and between end pieces, a swingable back member comprising an elongated frame having at least two adjacent spaced apart cross-pieces at each of its ends, a pivot pin projecting from each end of said frame and having a connection to the end pieces, each pivot pin being located adjacent to that side of said frame which is lowest and extending through both the cross-pieces at each end of the frame respectively and projecting therebeyond into the adjacent end piece which affords a bearing for the projecting portion of said pivot pin, and legs carried by the free side portion of said swingable back member.

7. The subject matter of claim 3 and, said latching means comprising stationary parts carried by said end pieces and movable parts carried by said back member, said movable parts, when in the latched position, overlying the free end portions of said legs to maintain them in an inswung relation to said back member.

8. The subject matter of claim 3 and, said latching means comprising stationary parts carried by said end pieces and hooked members pivoted to said back member, said hooked members each having a hook at one side of its pivotal mounting and a tailpiece at the opposite side thereof, said tailpiece being positionable to overlie the free end portions of said legs to keep them in an inswung relation to said back member when the hooks are in engagement with the aforesaid stationary parts of the latching means.

40 IRVIN C. POSKIN.
